US00D817903S

(12) **United States Design Patent** (10) Patent No.: **US D817,903 S**
(45) Date of Patent: **** May 15, 2018**

(54) **TELEVISION RECEIVER**

(71) Applicant: **LG ELECTRONICS INC.**, Seoul (KR)

(72) Inventors: **Hyojin Won**, Seoul (KR); **Yongho Lee**, Seoul (KR)

(73) Assignee: **LG ELECTRONICS INC.**, Seoul (KR)

(**) Term: **15 Years**

(21) Appl. No.: **35/501,341**

(22) Filed: **Feb. 3, 2016**

(80) **Hague Agreement Data**

Int. Filing Date: **Feb. 3, 2016**

Int. Reg. No.: **DM/090627**

Int. Reg. Date: **Feb. 3, 2016**

Int. Reg. Pub. Date: **Aug. 5, 2016**

(30) **Foreign Application Priority Data**

Aug. 5, 2015 (KR) 30-2015-0039669

(51) LOC (11) Cl. **14-03**

(52) U.S. Cl.
